United States Patent Office

Des. 191,641
Patented Oct. 24, 1961

191,641

BOTTLE

Ernest L. Du Pree, New York, N.Y., assignor to Schenley
Industries, Inc., New York, N.Y., a corporation of Delaware

Filed Mar. 8, 1961, Ser. No. 64,194

Term of patent 14 years

(Cl. D58—6)

FIGURE 2 is a top plan view thereof, with a portion broken away to show the cylindrical body portion; and

I claim:

The ornamental design for a bottle, as shown and described.
